UNITED STATES PATENT OFFICE.

PHILIP W. MOORE, OF EVANSTON, ILLINOIS, ASSIGNOR TO THE P. & M. CO., OF CHICAGO, ILLINOIS, A CORPORATION OF ILLINOIS.

ANTICREEPER FOR RAILS.

1,084,288.

Specification of Letters Patent. Patented Jan. 13, 1914.

Application filed October 16, 1912. Serial No. 725,976.

To all whom it may concern:

Be it known that I, PHILIP W. MOORE, a citizen of the United States, residing at Evanston, in the county of Cook and State 5 of Illinois, have invented a certain new and useful Improvement in Anticreepers for Rails, of which the following is a full, clear, concise, and exact description, reference being had to the accompanying drawings, 10 forming a part of this specification.

My invention relates to anti-creepers for rails.

The object of the invention is to provide improved means for automatically locking 15 the parts of the anti-creeper to each other to prevent loosening and possible disengagement from the rail.

In order to better explain the features of the invention I have illustrated two embodiments thereof. The invention is not limited 20 to these embodiments, however.

In the drawings: Figure 1 is an elevation of one form of anti-creeper, a portion of the rail being shown in sectional elevation. Fig. 25 2 is a top plan view thereof, with the rail and cross-tie indicated in dotted outline. Fig. 3 is a perspective view of one of the members of the anti-creeper, and Fig. 4 is a perspective view of the other member. Fig. 30 5 is an elevation of a second form of anti-creeper shown as applied to the rail. Fig. 6 is a top plan view thereof. Figs. 7 and 8 are perspective views of the two members which make up the anti-creeper.

The anti-creeper is made up of two parts 35 in both forms of device illustrated, although a greater number of parts may, of course, be employed. These parts are made preferably of malleable metal. The larger of the 40 two parts 1, may be called the clip. The smaller of the two parts 2, may be called the mate. The clip is provided with a jaw 3, adapted to fit over and grip one side of the base of the rail 4, said jaw being suitably 45 reinforced by flanges 5. The mate is provided with a similar jaw 6, which is suitably reinforced by flanges 7. The clip is provided with a slot or recess in its upper face, one side wall 8 of which is slightly undercut 50 as shown particularly in Figs. 1 and 3, and acts as an engaging face for a corresponding face 9, on the mate, said latter face being one of the sides of a rib 10, which rib is adapted to be received within the slot in the clip. 55

As shown in Fig. 2, the engaging faces of the clip and the mate are not exactly parallel with the longitudinal axis of the rail, but are arranged at an angle thereto. In assembling the rail anchor, the clip is applied to the rail as shown in said figure, with the downwardly extending tie abutting flange 11, bearing against the side of the cross-tie 12. The mate is applied to the rail at the end of the clip away from the cross-tie and is then driven toward the tie to approximately the position shown in Fig. 2, the engaging faces 8 and 9 acting as wedging surfaces which draw the jaws 3 and 6 toward each other into firm engagement 60 with the rail base. As long as the rail tends to creep in the direction of the arrow in Fig. 2, the tendency of the mate is to advance with the rail, and thereby increase the wedging engagement of the parts, any advance 65 of the clip being prevented by the cross-tie. If the rail should move in the reverse direction, however, due to contraction in cold weather or due to a reversal of traffic, for example, the effectiveness of the engagement 70 of the clip with the mate might be decreased under certain conditions. To prevent a rearward movement of the mate and the consequent loosening of the engagement 75 of the parts, I provide a locking tongue 13, which extends rearwardly from the clip in substantially a vertical plane. The rib 10 on the mate does not extend rearwardly the 80 entire length thereof but terminates in a locking face 14, as shown in Fig. 4. Adjacent to this locking face and slightly to the rear thereof, a cam surface 15 is provided, which engages the tongue 13 when the mate is being driven forward, and thereby deflects the same and bends it over the locking 85 face 14. The locking tongue and in fact the 90 entire clip being made of malleable metal, this bending may take place without danger of breaking off the tongue. Accordingly, said locking tongue has a positive locking 95 engagement with the corner or edge at the side of said locking face, thereby preventing movement of either of the members of the anti-creeper in a direction to decrease 100 their wedging engagement. It will be seen 105 that the locking tongue 13 is relatively short

and is deflected into a notch formed in the mate at a point between the front and the rear walls of said mate, and hence when deflected does not project rearwardly from the anti-creeper as a whole.

In the form of anti-creepers shown in Figs. 5, 6, 7 and 8, the main elements of the device are substantially the same as those previously described, and the same reference characters have been applied thereto. The locking tongue 16 is inclined in a reverse direction from that previously illustrated, however, and when engaged by the cam surface 17 is deflected across the locking face 18, which constitutes the rear of the diagonal rib or wall 10. The tongue 16 is deflected away from the jaw 3, instead of toward the same, as in the first case illustrated. Said tongue does not project to the rear of the anti-creeper, however, but is protected in this form of device also.

In both devices, the mate is driven into the clip as far as circumstances will permit, the locking tongue serving to lock the parts in any one of a number of possible relative positions. Furthermore, the effective operation of the lock is not dependent on any accurate predetermined degree of adjustment of the parts, as said lock permits considerable latitude in this regard.

It is apparent that various forms of anti-creeper may be devised and that various changes may be made in the details of those forms described herein without departing from the spirit of the invention, as expressed in the appended claims.

What I claim as new and desire to secure by Letters Patent of the United States is:

1. In an anti-creeping device, a plurality of engaging members, rail gripping means on two of said members, certain of said members being relatively movable to decrease the transverse distance between said rail gripping means, a single locking tongue projecting from the rear of one of said members, and means toward the rear of the other of said members for automatically deflecting said tongue against a vertical locking shoulder thereon.

2. A rail anchor comprising two rail gripping members, one of said members having a diagonally arranged slot, the other of said members having a diagonally arranged rib

adapted to be received within said slot, said first member being provided with a rearwardly projecting tongue adapted to be deflected into a notch in said rib when said members are moved relatively.

3. An anti-creeper for rails comprising two members each having rail gripping jaws, one of said members having a channel arranged nearly parallel to the rail base, the other of said members having a rib adapted to be received in said channel, said rib having a notch therein intermediate its ends, said other member having a projecting tongue adapted to be deflected into said notch.

4. A rail anchor comprising a plurality of members having interlocking wedging engagement beneath the rail base, said wedging engagement being effected by a diagonally arranged rib on one of said members which is received in a corresponding slot in the other of said members, said rib having an intermediate notch therein and having also a cam surface, said other member having a short tongue projecting from the rear thereof, whereby it may be deflected by said cam surface into said notch when said parts are being assembled, whereby said tongue locks said parts together without projecting from the rear thereof.

5. An anti-creeper for rails comprising a clip and a mate, said clip having a rail engaging jaw, a tie abutting flange and a diagonally arranged slot, said mate having a rail engaging jaw and a diagonally arranged rib adapted to slide within said slot, said rib being shorter than said mate, a shoulder at the rear of said rib, said mate having a notch adjacent to said shoulder, one of the walls of said notch forming a cam surface, and a tongue on said clip projecting rearwardly therefrom, substantially in line with one wall of said slot, whereby said tongue is engaged by said cam surface and deflected over said shoulder when the parts are being assembled.

In witness whereof, I hereunto subscribe my name this 28th day of September, A. D. 1912.

PHILIP W. MOORE.
